UNITED STATES PATENT OFFICE.

EDWIN CROMPTON, JR., OF PUEBLO, COLORADO, ASSIGNOR OF ONE-HALF TO FRANCES MONTGOMERY SIMPSON AND ONE-HALF TO EJA LAW SNYDER, BOTH OF PUEBLO, COLORADO.

LATCH.

1,132,705.

Specification of Letters Patent. Patented Mar. 23, 1915.

Application filed June 12, 1914. Serial No. 844,747.

To all whom it may concern:

Be it known that I, EDWIN CROMPTON, Jr., a citizen of the United States, residing at Pueblo, in the county of Pueblo and State 5 of Colorado, have invented a new and useful Latch, of which the following is a specification.

The present invention appertains to door latches or catches, and aims to provide a 10 novel and improved device of that nature.

The present invention contemplates the provision of a catch device of unique construction, and operable to hold a door, or the like, in closed position, but enabling the 15 door to be readily pushed open.

Another object of the present invention is to provide a door catch or latch, of novel construction, and having combined therewith, means for preventing the catch or 20 latch from being released when engaged by the keeper or striking plate.

It is also within the scope of the present invention, to provide a device of the nature specified, which will be comparatively 25 simple, non-encumbering, and inexpensive in construction, which may be readily applied to the free edge of a door, and which will be convenient, practical, and efficient in its use.

With the foregoing and other objects in view which will appear as the description proceeds, the invention resides in the combination and arrangement of parts and in the details of construction hereinafter 35 described and claimed, it being understood that changes in the precise embodiment of the invention herein disclosed, can be made within the scope of what is claimed, without departing from the spirit of the invention.

The invention has been illustrated in its preferred embodiment in the accompanying drawing, wherein:

Figure 1 is a vertical section taken 45 through the improved latch device, the section being taken on the line 1—1 of Fig. 2. Fig. 2 is a view looking toward the free edge of the door and illustrating the latch device, this view being taken on the line 50 2—2 of Fig. 1. Fig. 3 is a horizontal section taken on the line 3—3 of Fig. 1. Fig. 4 is a perspective view of the keeper or strike plate.

The present device embodies a face plate 1 adapted to be secured to the free edge of a

door 2, by means of screws or other securing members 3 passed through apertures provided in the upper and lower end portions of the face plate 1 and taking into the door. The frame of the device further includes a pair of cheek or side plates 4 and 5, which may be secured rigidly to the edge portions of the plate 1 adjacent its upper end.

In applying the frame to the door 2, the free edge of the door is provided with a recess or cavity 6, preferably opening at one side or face of the door, the face plate 1 being secured over the mouth or open end of the recess 6, the cheek or side plate 4 fitting within and against the side wall of the recess, and the side or cheek plate 5 being disposed over the open side of the said recess and having its edge portions overlapping and secured to the corresponding side or 75 face of the door.

The face plate 1 is provided with a vertical slot or elongated opening 7, the upper end of which is rounded, and the lower end of which is square. The upper end of the opening or slot 7 is disposed adjacent the mouth of the recess 6, and the said opening or slot 7 extends downwardly below the bottom of the said recess to a point adjacent the lower end of the face plate 1.

The latch or catch proper is in the form of a flat or leaf spring 8 disposed within the slot or opening 7 of the face plate and having its lower end secured to the inner side of the lower end portion of the face plate by means of rivets or other securing members 9, the lower screw 3 also being passed through the lower end of the leaf spring 8, to clamp the lower end of the leaf spring against the door 2 with the lower end 95 of the face plate. To enable the spring 8 to flex inwardly, the free edge of the door is provided with a shallow tapered recess 6^a forming an extension leading from the recess 6 in back of the leaf spring 8, whereby the upper end of the leaf spring may flex inwardly.

The upper or free end of the leaf spring 8 is provided with a semi-spherical or rounded knob 10 bulged or struck outwardly therefrom and normally projecting beyond the face plate 1. The knob 10 is disposed snugly within the upper end of the slot or opening 7 of the face plate, and is adapted to be sprung or pressed inwardly into the recess 6.

The keeper or striking plate 11, which is secured to the jamb 12 of the door frame or casing, is provided with a dished or inwardly bulged portion 13 providing a socket 5 for receiving the knob 10, and one edge of the keeper or striking plate 11 is provided with an instruck curved lip 14 for facilitating the engagement and disengagement of the knob 10 with and from the keeper or 10 striking plate.

As a means for locking the knob 10 of the latch or catch in projected or normal position, a spindle 15 is journaled through the cheek or side plates 4 and 5 adjacent their 15 lower edges, and adjacent the bottom of the recess 6, and is provided beyond the cheek or side plate 5 with a knob or thumb piece 16. The spindle 15 is provided between the plates 4 and 5, with a radial finger 17, the 20 tip or free end of which is adapted to be swung into the dished or bulged knob 10, the finger 17 being of sufficient length in order that its free end will snap past the upper end of the leaf spring 8 as the finger 17 is 25 swung into and out of engagement with the latch or catch.

After the present device has been applied, which may be readily accomplished, and when the spindle 15 is turned to bring the 30 finger 17 to idle or inoperative position, as seen in full lines in Fig. 1, the door 2 may be readily pushed open and closed without difficulty. When the door is closed, the knob 10 moving over the lip 14 of the keeper or 35 striking plate, will press the knob 10 back into the recess 6, and the knob will then be projected within the socket 13 of the keeper or striking plate under the tension or influence of the spring 8, to hold the door 40 yieldably closed. Thus, when pressure is applied to the door, the same will readily open, inasmuch as the knob 10 will be forced back into the recess 6, to become released from the keeper or striking plate 11. Thus, 45 when the locking finger 17 is released from

the catch or latch 8, the door may be readily swung to closed and open positions, without difficulty, and when closed, will be held in such position, without being blown open by a gust of wind, or the like.

50

To lock the door in closed position, it is merely necessary to turn the spindle 15, through the medium of the thumb piece 16, so as to swing the free end of the finger 17 within the dished knob 10, to thereby prevent the knob from being sprung into or retracted within the recess 6. This will prevent the door from being opened, until the finger 17 is swung out of engagement with the latch or catch. The free end of the 60 finger 17 is preferably arranged to snap past the upper end of the latch or catch, to prevent the accidental disengagement of the finger 17 from the latch or catch, when the latch or catch is locked in projected position.

65

The present device may be inexpensively manufactured, the same being comparatively simple, and may be applied to a door without difficulty. The other advantages will be obvious from the foregoing, taken in connection with the drawing, without further comment being deemed necessary.

70

Having thus described the invention, what is claimed as new is:—

In a device of the character described, a 75 face plate having a slot therein, a leaf spring disposed within the said slot and having one end secured to the face plate adjacent one end of the slot, the leaf spring having an outwardly bulged knob at its free end, 80 and a rotatable spindle having a finger engageable within the said knob to hold it in projected position.

In testimony that I claim the foregoing as my own, I have hereto affixed my signature in the presence of two witnesses.

EDWIN CROMPTON, JR.
